UNITED STATES PATENT OFFICE.

THOMAS L. MURPHY, OF NEW YORK, N. Y.

DESIGN FOR A PUMP-FRAME.

SPECIFICATION forming part of Design No. 26,591, dated February 2, 1897.

Application filed December 21, 1896. Serial No. 616,540. Term of patent 7 years.

To all whom it may concern:

Be it known that I, THOMAS L. MURPHY, a citizen of the United States, residing in the city, county, and State of New York, have invented and produced a new and original Design for Pump-Frames, of which the following is a specification, reference being had to the accompanying drawing, showing a part thereof.

10 The figure represents a perspective view of a pump case or frame constructed according to my improved design.

A B represent cylinders which are alined with one another, and C represents a central 15 connecting frame or case to which the cylinders A B are integrally joined, the whole

forming a single box of the design represented in the drawing.

The leading feature of my design consists in a pump-frame having an enlarged central 20 portion or swell C of box form and reduced cylindrical portions A B, projecting on diametrically opposite sides of said central portion.

What I claim is—

25 The design for pump-frames substantially as shown.

THOMAS L. MURPHY.
